UNITED STATES PATENT OFFICE.

MERRILL KENNETH PAINE, OF WEBSTER CITY, IOWA.

IDENTIFICATION MEANS FOR LEDGER SHEETS AND THE LIKE.

Application filed January 11, 1922. Serial No. 528,364.

To all whom it may concern:

Be it known that I, MERRILL KENNETH PAINE, a citizen of the United States of America, and resident of Webster City, 5 Hamilton County, Iowa, have invented a new and useful Identification Means for Ledger Sheets and the like, of which the following is a specification.

The object of this invention is to provide 10 a convenient identification means applicable to ledger sheets used in banks for posting customers' accounts.

A further object of this invention is to provide improved means for locating a customer's 15 signature slip on a ledger sheet used for posting his account, so that it may be referred to instantaneously during the posting of each debit item, or whenever occasion arises.

20 A further object of this invention is to safeguard a bank in posting checks and the like by providing means for removably and replaceably mounting a signature slip on the ledger sheet of the account where it can be 25 readily referred to.

My invention consists in the construction, arrangement and combination of elements 30 hereinafter set forth, pointed out in my claim and illustrated by the accompanying drawing, in which—

Figure 1 is a face view of a ledger sheet equipped with my improved identification means. Figure 2 is a cross-section on the line 2—2 of Figure 1. Figure 3 is a section 35 at right angles to Figure 2, on the line 3—3 of Figure 1, on an enlarged scale. Fig. 4 is a face view and Fig. 5 a cross-section on the line 5—5, showing a modified form.

In the construction of the device or article 40 of manufacture as shown the numeral 10 designates generally a sheet such as is commonly employed by banks and the like for posting customer's checking accounts, space being provided, among other things, for entering all checks drawn by the customer 45 against his account. Under the system now largely employed, these sheets are of the loose-leaf variety and are removable for insertion in a typewriting or posting machine 50 for the purpose of making the entries. The common practice is to have an identification or signature card for each customer and these cards are all kept together in a card-index file or similar device. When the book- 55 keeper feels it is necessary or desirable to compare a signature on a check with the

signature card on file, he must go to the proper file, search out the signature card in question, and make his comparison, a proceeding which takes some little time and trouble and is apt to be neglected at times to the detriment of the institution. It is my purpose in the present invention to provide a signature slip which may be mounted on each sheet of the account and which can be 60 referred to at a glance at any time by the bookkeeper as he makes his entries, the identifying signature thus being before him at all times as he enters items of a given account. 70

A transparent pocket is provided and is affixed to and carried by the sheet 10 in any suitable location, as at an upper corner thereof. The pocket is formed by a transparent window member of celluloid, 75 isinglass or other similar substance, preferably of a flexible nature, here designated by the numeral 11. This transparent member 11 is affixed to the sheet 10 along three margins, as by suitable gum, thus providing an end 80 opening pocket adapted to receive a slip 12 bearing a signature such as 13 applying to the account carried by the individual ledger sheet. The identification or signature slip 12 is of flexible material such as paper or 85 light cardboard and preferably is of somewhat greater length than the pocket formed by the window 11, so that when said slip is in place in said pocket one end projects through the open end of said pocket. Thus 90 the slip 12 may be readily grasped between a thumb and finger for removing or adjusting it upon occasion. 95

A groove 14, forming three sides of a rectangle, or a depression or countersink, 100 preferably is formed in the surface of the sheet 10 at the desired location of the transparent pocket and preliminary to mounting the member 11 thereon. This depression or groove is adapted to receive the 105 three marginal gummed portions of the transparent member 11 whereby such gummed margins are countersunk to or below the surrounding surface of the sheet 10, thus facilitating the insertion of the 110 sheet within a typewriting or posting machine without damage to or interference by the member 11 mounted thereon. It will be noted that the open margin of the transparent member, which is not received within the groove 14, is at one end and parallel 115 to the direction of travel of the sheet when

being introduced to or removed from a machine such as above mentioned.

One of the transparent window members 11 preferably is mounted on each face of the sheet 10, as shown in Figure 2, so that said sheet when reversed may be supplied with the identification means, the slip 12 being removed from its primary location on the face of the sheet first used and inserted in the pocket on the other face.

By this means the identification or signature slip is always before the bookkeeper as he enters each item and possibility of fraudulent items escaping detection is greatly reduced, as well as resulting in considerable saving of time in making the comparisons which are frequently necessary. It is thought best to provide these removable slips 12 in addition to the regular signature card ordinarily employed and kept in the regular files.

It is apparent that this identification means may be adapted to or employed in connection with other than the bank ledger sheets here referred to, and I do not wish to be understood as unduly limiting myself to such use.

In the construction according to Figures 4 and 5 the sheet 10^a is formed with the depression or groove 14' as before but the transparent member is omitted. In lieu thereof, and to provide holding means for an identification slip such as 12, the sheet is formed with spaced parallel slits connecting longer side portions of the groove 14', thus producing a plurality of strips 15, 16 extending in spaced relation across the pocket formed by said groove or depression, and adapted to hold the slip 12 in place 40 in such manner that the signature or other

identifying means thereon is visible, in the major portion at least, at all times by one using or referring to the ledger sheet. The slip 12 is removable and replaceable, as before, by endwise movement relative to the pocket and strips 15, 16, but the identifying means is not protected as by the transparent member, and the slip is not held in as stable relation as in the preferred construction. This construction is, however, much simpler and more economical to produce than the other and in most instances would be efficient and desirable.

In either form, the slip 12 may be made the exact length of the pocket, not projecting at one end therefrom, so that it will not interfere with introduction of the sheet to the rollers of a typewriting or posting machine.

In the modified form it may be desirable to extend the groove or pocket 14' around all four sides of the slip, which will tend to hold the slip in place, it being of not greater length than the pocket so formed.

I claim as my invention—

A ledger sheet formed to produce in one face spaced parallel grooves and on the opposite face corresponding ridges outlining two sides of an integral pocket, retaining means extending across the face of said pocket, and an identification slip adapted to be mounted in said pocket and retained by said retaining means, said ridges extending across and protecting the edges of said slip.

Signed at Webster City, in the county of Hamilton and State of Iowa, this 19th day of December, 1921.

MERRILL KENNETH PAINE.
